(57) **CLAIM**

The ornamental design for a rubberized magnetic holder as shown and described.

DESCRIPTION

FIG. 1 is a front-top perspective view of a rubberized magnetic holder in accordance with the present invention.

FIG. 2 is a bottom-rear perspective view thereof.

FIG. 3 is a front view thereof.

FIG. 4 is a rear view thereof.

FIG. 5 is a left side view thereof, the right side view being a mirror image.

FIG. 6 is a top view thereof; and,

FIG. 7 is a bottom view thereof.

The broken lines in the drawings form no part of the claimed design.
